Attorney

UNITED STATES PATENT OFFICE.

VICTOR E. LEET, OF GREENVILLE JUNCTION, MAINE.

SNOWSHOE HARNESS.

Application filed April 2, 1923. Serial No. 629,400.

To all whom it may concern:

Be it known that I, VICTOR E. LEET, a citizen of Canada, residing at Greenville Junction, in the county of Piscataquis and State of Maine, have invented certain new and useful Improvements in Snowshoe Harnesses, of which the following is a specification.

The present invention relates to a snow shoe harness, and has for its object to provide a device of this character which embodies novel features of construction whereby the foot can readily be attached to a snow shoe in such a manner as to permit of the necessary freedom of action and prevent snow and ice from accumulating in an objectionable manner between the snow shoe and the bottom of the foot.

Further objects of the invention are to provide a snow shoe harness which is comparatively simple and inexpensive in its construction, which can be used in connection with any conventional form of snow shoe, and which can be used in connection with any form of foot wear, such as over-shoes, rubbers, moccasins and the like.

With the above and other objects in view, the invention consists in certain combinations and arrangements of the parts as will more fully appear as the description proceeds, the novel features of the invention being pointed out in the appended claims.

For a full understanding of the invention reference is to be had to the following description and accompanying drawings, in which,

Figure 1 is a perspective view of a snow shoe harness which is constructed in accordance with the invention, fragmentary portions of a snow shoe to which the harness is connected being also shown.

Figure 2 is a perspective view showing the manner of using the harness to attach a foot to a snow shoe.

Figure 3 is a detail view showing a slight modification.

Corresponding and like parts are referred to throughout the following description and indicated on all of the views of the drawings by like reference characters.

For illustrative purposes the invention is shown as used in connection with a snow shoe A which is of the conventional construction. The frame of the snow shoe is connected at a suitable point by a transverse strip

or thong 1 to which the harness is attached. The harness includes a toe strap 2 which is connected at opposite ends to anchor rings 3. These anchor rings 3 are fitted loosely upon the thong or cross strip 1 of the snow shoe, and the toe strap is formed in sections which are adjustably connected by the buckle 4, so that the strap can be drawn firmly around the toe of the foot.

An instep strap 5 is arranged in a spaced relation to the toe strap and has the ends thereof connected to rings 6. These rings 6 are connected to the before mentioned anchor rings 3 by side straps 7, and a bottom strap 8 which extends under the foot connects the two rings 6. The instep strap 5 is formed in sections which are connected by a buckle 9, so that the strap can be drawn tightly around the instep of the foot.

The manner of using the snow shoe harness is illustrated by Figure 2, and it will be seen that there is no heel strap, and that the heel of the foot is not directly connected to the snow shoe, but is free to move up and down relative to the snow shoe. In using the harness it is not necessary to wear moccasins or any special form of footgear, but the harness can be used with equal facility in connection with over-shoes, rubbers, moccasins or any kind of foot wear. Another advantage of this snow shoe harness is that there is nothing between the foot and the snow shoe to hold the snow and ice, and objectionable accumulations of snow and ice will not form between the foot and the snow shoe. The harness is attached to the snow shoe by the anchor rings 3, and the foot is thus free to swing upon the thong or strip 1 in order to give the wearer the necessary freedom of movement, different positions of the foot being indicated on Figure 2 by full lines and dotted lines respectively.

A slight modification is shown by Figure 3 by which the side straps 7 are formed with buckles 10, thereby enabling the length of the side strap to be regulated as may be necessary to fit the harness to different sizes of feet.

One particular embodiment of the invention has been illustrated in detail, although it will be understood that certain modifications and changes can be made in the details of construction without departing from the spirit of the invention.

Having thus described my invention what

I claim as new and desire to secure by Letters Patent is,

1. The combination with a snow shoe formed with a cross strap, of a pair of anchor rings loosely mounted upon the cross strap, so that they are free to move toward and away from each other, and a plurality of associated foot engaging straps connected to the anchor rings.
- 10 2. The combination with a snow shoe formed with a cross strap, of a pair of anchor rings loosely fitted upon the cross strap and slidable thereon toward and away from each other, a toe strap connecting the anchor rings, and an instep strap also connected to

the anchor rings and cooperating with the toe strap to engage the foot.

3. The combination with a snow shoe formed with a cross strap, of a pair of anchor rings loosely mounted upon the cross strap and slidable toward and away from each other, a toe strap connecting the anchor rings, an instep strap, a bottom strap cooperating with the instep strap to encircle the foot at the instep portion thereof, and side straps connecting the instep and bottom straps to the anchor rings.

In testimony whereof I affix my signature.

VICTOR E. LEET.
